UNITED STATES PATENT OFFICE.

CHARLES E. BRUNTHAVER, OF WASHINGTON, DISTRICT OF COLUMBIA.

COPY-HOLDER.

SPECIFICATION forming part of Letters Patent No. 431,934, dated July 8, 1890.

Application filed May 15, 1890. Serial No. 351,886. (No model.)

To all whom it may concern:

Be it known that I, CHARLES E. BRUNTHAVER, a citizen of the United States, residing at Washington, in the District of Columbia, have invented certain new and useful Improvements in Copy-Holders; and I do hereby declare the following to be a full, clear, and exact description of the invention, such as will enable others skilled in the art to which it applies to make and use the same.

This invention relates to that class of indicators which are adapted to show by successive steps a series of objects—such as the names of stations on a railroad or of street-crossings on a street-car line—or to show a series of parts occurring in the same object—such as lines of proof-sheet to be read or of writing to be copied, or such as the names of periods of time on a calendar, &c.; and the object of this invention is to simplify and to render more reliable and accurate the operation of my earlier invention, on which an application, Serial No. 344,622, was filed in the Patent Office March 20, 1890, to adapt it particularly as a copy-holder for use with typewriting machines, &c.

To this end my invention consists in the construction and combination of parts forming a copy-holder hereinafter described and claimed, reference being had to the accompanying drawings, in which—

Figure I is a front elevation of my copy-holder. Fig. II is an end view of the same with certain parts broken away to show parts beyond; and Fig. III represents a vertical section at *x*, Fig. I.

5 represents the bed-piece, adapted to rest upon any table.

6 are the two end portions of the frame, secured by screws to the bed-piece and connected together by a cross-bar 7, having a wooden portion 8 secured to it.

9 10 represent cylindrical rollers journaled in the ends 6. The lower roller 10 is in permanent bearings, but the upper roller 9 is free to rise and fall in its bearings, and is pressed down by a spring 11 and follower 12 at each end to insure its pressure upon the paper 13, which is the copy to be passed between the rollers. The roller 10 is provided with a knob 14, by means of which it may be rolled rapidly

forward to draw the copy or other paper into place, and with a gear-wheel 15, engaging an intermediate gear-wheel 16, that is journaled to revolve freely upon a stud 17, which is fixed 55 to the frame 6.

18 is a ratchet-wheel journaled upon the same stud 17 and rigidly fixed to the intermediate wheel 16.

19 is a lever provided with a finger-knob 20 and journaled upon the same stud 17, and further provided with a series of pawls 21, whose free ends are forced into engagement with the ratchet-wheel 18 by means of springs 22, one spring for each pawl. 60

23 is a slotted segment secured to the frame 6 and having an offset to carry its arc beyond the gear-wheels and lever.

24 is a stop-pin in the path of the lever 19, and made adjustable along the said segment 70 23 by means of a set-screw 25, passing through a screw-nut fitted to slide but not to turn in the slot in the segment.

26 is a spring coiled around and secured at its inner end to a hub of the lever 19 and secured at its outer end to a long screw 27, which stands as a fixed stud from the frame 6. The spring 26 pulls the lever 19 and pawls 21 backward until a shoulder of the lever rests normally against a shoulder 28 of the fixed segment 23. 75

29 is a drum neatly concealing the coil of the spring 26, but open at one side to permit the arm of the spring to reach its point of attachment 27. 80

39 is a sash provided with hinges 30, which attach it to the cross-bar 8 of the frame.

31 is a shield fitted to slide vertically in grooves 32 in the end bars of the sash.

33 is a plate or table secured by screws 34 90 to the ends of the frame and located tangent to the lower roller 10 and just below it to serve as a backing or table to support the paper should it be found necessary to write upon it while it is in the machine.

The operation is as follows: To insert the paper, first raise the sash 39 and swing it up out of the way. Then put the upper edge of the paper between the rollers 9 10 and by turning the knob 14 draw the paper in a little. 100 Then turn its lower end back under the plate 33, as shown in Fig. III. Now bring the sash

down to place in front of the paper. Then bring a line of the paper exactly to the upper edge of the shield 31. Press the lever 20 down until the next line on the paper is exactly at 5 the edge of the shield, and then by means of the thumb-screw 25 fix the stop-pin 24 against the lever. If this adjustment is accurately made, every pressure upon the lever will bring up another line of the copy. It will be observed that there are three pawls 21 of different lengths to engage a tooth one after another, so that whatever may be the space between lines some one of the pawls is ready to engage a tooth without loss of space. By 15 properly proportioning the gearing described this machine may be gaged to draw the copy along any space varying from one thirty-second of an inch to several inches at a step, so that it may be adapted for reading printed 20 proof in fine type or for reading copy in the widest-spaced writing. It is here shown with a bed-piece adapted to stand upon a table; but it would require only common mechanical skill to provide a clamp-screw whereby this copy-holder may be attached conveniently to the 25 frame of a type-writing machine. Its means of adjustment render it applicable to a great many uses not here enumerated.

Having thus fully described my invention, 30 what I believe to be new, and desire to secure by Letters Patent, is the following:

1. The combination, in copy-holders, of a frame, two cylinders journaled therein one above the other and one of them provided with 35 a gear-wheel, an intermediate wheel journaled upon a stud fixed on the frame and gearing with the aforesaid wheel and having a ratchet-wheel fixed to it, a lever journaled upon the said stud and provided with a series of pawls 40 and springs to engage the aforesaid ratchet-

wheel, a spring for returning the lever, a fixed stop at one end of the path of the lever, and a stop adjustably fixed in its path, substantially as shown and described.

2. The combination, in copy-holders, of two 45 feed-rollers journaled in a frame and one of them provided with a gear-wheel, an operating-lever journaled upon a stud fixed on the frame and provided with pawls, a ratchet-wheel engaged by the said pawl and fixed to 50 an intermediate wheel journaled upon the said stud and gearing with the said wheel upon the roller, a slotted segment fixed to the frame and having a shoulder ending the path of the said lever, and a stop-pin provided with 55 a screw-nut adjustable along the slot in the said segment in the path of the lever, substantially as shown and described.

3. The combination, in copy-holders, of two feed-rollers journaled in a frame, a sash having a shield in it hung in front of the rollers, and an aperture through the sash above the shield, and a plate fixed nearly tangent to the lower roller between the same and the said shield, substantially as shown and described. 60

4. The combination, in copy-holders, of two feed-rollers journaled in a frame and a sash hung in front of the rollers upon hinges and having an aperture exposing to view the region of the rollers, substantially as shown and 65 described, whereby the rollers may be uncovered to place the paper between and below them and then the paper be partially concealed.

In testimony whereof I affix my signature in 70 presence of two witnesses.

CHARLES E. BRUNTHAVER.
